UNITED STATES PATENT OFFICE

116,977

DESIGN FOR A TOILET CASE OR SIMILAR ARTICLE

Henri Bellau, Paris, France

Application June 7, 1938, Serial No. 77,654
In Great Britain December 11, 1937

Term of patent 3½ years

To all whom it may concern:

Be it known that I, Henri Bellau, a citizen of the Polish Republic, residing at Paris, in the Republic of France, have invented a new, original, and ornamental Design for a Toilet Case or Similar Article, of which the following is a specification, reference being made to the accompanying drawing, forming part thereof.

Fig. 1 is a perspective view of a toilet case or similar article embodying my new design in closed position; and

Fig. 2 is a perspective view thereof in open position.

The characteristic features of my design reside in the combination of the toilet case with the side arms *a*. The rear and other side of the case which are not seen are substantially plain and identical with the sides seen in the drawing.

I claim:

The ornamental design for a toilet case or similar article substantially as shown and described.

HENRI BELLAU,
